UNITED STATES PATENT OFFICE.

HENRY VAN HOEVENBERGH, OF ELIZABETH, NEW JERSEY.

TELEPHONE-CIRCUIT.

SPECIFICATION forming part of Letters Patent No. 308,020, dated November 11, 1884.

Application filed April 12, 1884. (No model.)

To all whom it may concern:

Be it known that I, HENRY VAN HOEVENBERGH, a citizen of the United States, residing in Elizabeth, in the county of Union and State of New Jersey, have invented certain new and useful Improvements in Telephone-Circuits, of which the following is a specification.

My invention relates to the organization of telephonic circuits; and its object is to provide means for overcoming the detrimental effects due to the static capacity of the main line and to induced charges.

Various means have been adopted for preventing or overcoming the static and induced charges which tend to be present on telephonic main lines when those lines are of considerable length. For example, condensers have been employed in such a manner that the charge and discharge of the same tend to some extent to counteract the effects of the charges, and it has also been proposed to employ various arrangements of metallic circuits, the direct and return conductors being so organized that currents traversing extraneous conductors exert little or no detrimental influence.

My invention consists in employing at each terminal of the telephonic conductor an induction-coil, the primary coil being included in the circuit of the main line, while the secondary coil is independently connected with the earth, or vice versa. Such an induction-coil possesses many of the qualities of, and in many respects is, in effect, a condenser. The transmitting and the receiving instruments are included in the main-line circuit in the usual manner, preferably at points between the earth and the coil which is connected with the main line. By employing an organization of this character I have found that the detrimental effects due to static charges upon the line which are otherwise manifest in a telephonic circuit are to a very great extent and in some instances entirely overcome.

In the accompanying drawings, which illustrate my invention, Figure 1 shows a form of induction-coil which I prefer to employ, and Fig. 2 illustrates the method of connecting the same in a telephonic circuit.

Referring to the drawings, A represents the core of the induction-coil, which consists of a

bundle of soft-iron wires. Surrounding this core are the two coils, B' and B'', of insulated wire. The primary coil B' is preferably divided into sections b', each section having any desired number of separate convolutions. From each section a conductor, c, leads to a corresponding contact or switch point, d. The switch-points d are applied to a switch-plate, D, and by means of a suitable switch-plug, e, any one of the sections may be connected directly with the switch-plate through the conductor c and point d. This construction is adopted for the purpose of rendering it possible to employ a greater or less number of convolutions of the primary coil in the circuit of the main line, as desired. When the induction-coils are placed in the circuit of the main line, it is intended that the main line shall be connected at its respective terminals with the plates D, as shown in Fig. 2, while the conductors f, leading to the earth, are connected with the remaining terminal of the primary coil of the induction-coil. A plug, e, is then employed for including as many of the sections of convolutions of the primary coil in the circuit of the main line as may be desired, and this is accomplished by inserting the plug in one or the other of the holes f between the plate D and the points d. One terminal of the secondary coil B'' of each induction-coil is connected directly with the earth by conductors f. The secondary and primary coils may, if desired, be interchanged with each other as regards their circuit-connections, the secondary coil being included in the main-line circuit instead of the primary coil.

The transmitting and receiving instruments are of any well-known form of construction, and they may be included in the circuit of the main line either between the induction-coils and the earth or between the main line and the induction-coils, as found desirable. Usually, however, I prefer the former organization.

It may in some instances be found desirable to connect both terminals of the secondary coils with the earth; but usually this is not necessary.

In another application for patent filed by me April 2, 1884, and numbered 126,422, I have shown and described an organization of apparatus in many respects similar to that

herein shown and described, and I do not therefore herein claim anything shown, described, and claimed in said other application and not specifically claimed herein.

5. I claim as my invention—

1. The combination, substantially as hereinbefore set forth, of a telephonic main line, a condenser located at or near each end of said main line, one arm of each condenser being connected with the earth and the other included in the circuit of said main line in series, and means for varying the length of the arm which is thus included in the main line.

2. The combination, substantially as hereinbefore set forth, with telephonic transmitting and receiving instruments and a main line uniting the same, of a condenser inserted in said main line at or near its respective terminals, and having one arm included in circuit therewith, and the other arm connected with the earth, and means, substantially such as described, for varying the static capacities of the portions of said condensers included in said main line.

25. 3. The combination, substantially as hereinbefore set forth, with a telephonic main line, of a condenser having the form of an induction-coil placed at or near its respective terminals, one coil of each of which is connected in circuit with the main line and the telephonic instruments, while the other coil is connected directly with the earth.

4. The combination, substantially as hereinbefore set forth, with a telephonic main line, 35 of a condenser having the form of an induction-coil, the primary coil of which is connected in the circuit of the main line together with the transmitting and receiving instruments, while the remaining coil is connected directly with the earth.

5. The combination, substantially as hereinbefore set forth, of a telephonic main line, a condenser having the form of an induction-coil, one coil of which is connected with the earth, while the remaining coil is connected 45 in the circuit of the main line together with the transmitting and receiving instruments, and means, substantially such as described, for varying the number of convolutions of the last-named coil which are included in series in the 50 main-line circuit.

6. The combination, substantially as hereinbefore set forth, of a telephonic main line, a condenser having the form of an induction-coil placed at its respective terminals, one of 55 the coils of said induction-coil being connected directly with the earth, while the other is connected in the circuit of the main line, and means for modifying the length of the conductor or which is included in the circuit of the main 60 line.

7. The combination, substantially as hereinbefore set forth, of a telephone main line, telephonic instruments connected therewith, and a condenser having the form of an induction-coil, one coil of which is divided into sections, 65 in combination with a series of conductors respectively leading from such sections, a series of switch-points to which said conductors lead, and a switch-plate to which said switch-points 70 are applied, substantially as described.

In testimony whereof I have hereunto subscribed my name this 11th day of April, A. D. 1884.

HENRY VAN HOEVENBERGH.
